ABSTRACT

Methods for installing curtain rod brackets and secure curtain rods to a wall with the curtain rod brackets. The methods involve installation of one or more curtain rod brackets having a back portion, an arm and a curtain rod cradle, and a fastening plate that is configured to engage a wall. The back portion is configured to slidably receive the fastening plate, and includes a channel formed with a pair of opposing side rails, an upper stop and a lower opening.

METHODS FOR INSTALLING CURTAIN ROD BRACKETS

CROSS REFERENCE TO RELATED APPLICATIONS

This application is a divisional of U.S. patent application Ser. No. 18/335,068, filed Jun. 14, 2023, which is a continuation in part of U.S. patent application Ser. No. 17/819,395, filed Aug. 12, 2022, which is a continuation of U.S. patent application Ser. No. 16/358,204, filed Mar. 19, 2019, and claims benefit from U.S. Provisional Patent Application Ser. No. 62/644,889, filed Mar. 19, 2018. All of these applications are incorporated by reference in their entireties.

STATEMENT REGARDING GOVERNMENT INTEREST

None.

BACKGROUND OF THE INVENTION

The present invention relates generally to curtain rods, and more particularly to an easily and quickly installed bracket for use with curtain rods.

In general, curtain rods and such are hung on brackets. In a typical installation, a bracket is placed in a desired position against a wall, the bracket secured to the wall using nails and/or screws, and a curtain rod positioned and suspended securely across the bracket. At a minimum, the installation of the bracket requires a hammer and/or a screwdriver to fixate the nails and/or screws and reasonable manual dexterity to secure the bracket to the wall. More specifically, the bracket is positioned on the wall, nails and/or screws are tap and/or screwed into the wall, and curtain and rod are hung on the bracket.

What is needed is a system that eases an installation of a curtain rod bracket to a wall structure.

SUMMARY OF THE INVENTION

The following presents a simplified summary of the innovation in order to provide a basic understanding of some aspects of the invention. This summary is not an extensive overview of the invention. It is intended to neither identify key or critical elements of the invention nor delineate the scope of the invention. Its sole purpose is to present some concepts of the invention in a simplified form as a prelude to the more detailed description that is presented later.

In general, in one aspect, the invention features a method comprising the steps of (1) providing a curtain rod bracket assembly comprising: (a) a back portion having a front surface and a channel with an upper stop member, first and second opposed side rails descending from the upper stop member, and a lower opening between the first and second side rails, (b) a first arm extending outward from a first portion of the front surface, and including a first end engaging the first portion and a second end opposite the first end, (c) a curtain rod receptacle engaging the second end of the first arm, and (d) a fastening plate configured to slidably engage the back portion channel, and configured to engage a wall, the fastening plate including first and second apertures dimensioned to receive first and second securing objects therein, respectively; (2) positioning the fastening plate of the curtain rod bracket assembly against the wall; (3) inserting the first securing object of the curtain rod bracket assembly into the first aperture of the fastening plate of the

curtain rod bracket assembly; (4) urging the first securing object of the curtain rod bracket assembly through the first aperture of the fastening plate of the curtain rod bracket assembly, whereby the first securing object enters the wall until a small portion of the first securing object is protruding out of the first aperture of the fastening plate of the curtain rod bracket assembly; (5) inserting the second securing object of the curtain rod bracket assembly into the second aperture of the fastening plate of the curtain rod bracket assembly; (6) urging the second securing object of the curtain rod bracket assembly through the second aperture of the fastening plate of the curtain rod bracket assembly, whereby the second securing object enters the wall until a small portion of the second securing object is protruding out of the second aperture of the fastening plate of the curtain rod bracket assembly; (7) sliding the back portion of the curtain rod bracket assembly onto the fastening plate of the first curtain rod bracket assembly such that the channel of the back portion receives the fastening plate therein, whereby the back portion of the curtain rod bracket assembly is secured to the fastening plate of the curtain rod bracket assembly and thus to the wall; and (8) positioning a curtain rod within the curtain rod receptacle of the curtain rod bracket assembly.

25 In another aspect, the invention features a method comprising the steps of (1) providing a curtain rod bracket assembly comprising: (a) a back portion having a front surface and a channel with an upper stop member, first and second opposed side rails descending from the upper stop member, and a lower opening between the first and second side rails, (b) a first arm extending outward from a first portion of the front surface, and including a first end engaging the first portion and a second end opposite the first end, (c) a curtain rod receptacle engaging the second end of the first arm, and (d) a fastening plate configured to slidably engage the back portion channel, and configured to engage a wall, the fastening plate including first and second apertures dimensioned to receive first and second securing objects therein, respectively; (2) positioning the fastening plate of the curtain rod bracket assembly against the wall; (3) inserting the first securing object of the curtain rod bracket assembly into the first aperture of the fastening plate of the curtain rod bracket assembly; (4) urging the first securing object of the curtain rod bracket assembly through the first aperture of the fastening plate of the curtain rod bracket assembly, whereby the first securing object enters the wall until a small portion of the first securing object is protruding out of the first aperture of the fastening plate of the curtain rod bracket assembly; (5) inserting the second securing object of the curtain rod bracket assembly into the second aperture of the fastening plate of the curtain rod bracket assembly; (6) urging the second securing object of the curtain rod bracket assembly through the second aperture of the fastening plate of the curtain rod bracket assembly, whereby the second securing object enters the wall until a small portion of the second securing object is protruding out of the second aperture of the fastening plate of the curtain rod bracket assembly; and (7) sliding the back portion of the curtain rod bracket assembly onto the fastening plate of the first curtain rod bracket assembly such that the channel of the back portion receives the fastening plate therein, whereby the back portion of the curtain rod bracket assembly is secured to the fastening plate of the curtain rod bracket assembly and thus to the wall.

30 These and other features and advantages will be apparent from a reading of the following detailed description and a review of the associated drawings. It is to be understood that

both the foregoing general description and the following detailed description are explanatory only and are not restrictive of aspects as claimed.

BRIEF DESCRIPTION OF THE DRAWINGS

These and other features, aspects, and advantages of the present invention will become better understood with reference to the following description, appended claims, and accompanying drawings where:

FIG. 1 is an illustration of a first embodiment of an exemplary fast fit bracket system.

FIG. 2 is an illustration of a second embodiment of an exemplary fast fit bracket system.

FIG. 3 is an illustration of an exemplary back channel of a bracket.

FIG. 4 illustrates an exemplary prong.

FIG. 5 illustrates an exemplary alignment of a prong relative to channel of a bracket.

FIG. 6 illustrates an alternate fastening plate.

FIG. 7 illustrates an exemplary rear view of a fast fit bracket system.

FIG. 8 illustrates an exemplary bottom view of a fast fit bracket system.

FIG. 9 illustrates an exemplary side view of a fast fit bracket system.

DETAILED DESCRIPTION

The subject innovation is now described with reference to the drawings, wherein like reference numerals are used to refer to like elements throughout. In the following description, for purposes of explanation, numerous specific details are set forth in order to provide a thorough understanding of the present invention. It may be evident, however, that the present invention may be practiced without these specific details. In other instances, well-known structures and devices are shown in block diagram form in order to facilitate describing the present invention.

As shown in FIG. 1, a first embodiment of an exemplary fast fit bracket system 100 includes a bracket 110 and a fastening plate 120 having apertures 122, 124 to receive finishing nails 126, 128, respectively. In a preferred embodiment, an angle of the apertures 122, 124 is 45 degrees relative to the fastening plate 120. It should be appreciated that the shape and design of the bracket 110 can vary. In addition, it should be appreciated that the finishing nails 126, 128 may be replaced with other securing objects, such as screws. In the example embodiment, the bracket 110 includes a back portion 130, a first arm 140, a second arm 145 and a curtain rod cradle 150. The back portion 130 comprises a front surface 115 and includes a channel 132 formed with a pair of opposing side rails 136, 138, an upper stop member 134 and a lower opening 139. The first arm 140 extends outward from a first portion of the front surface 115 and includes a first end 142 engaging the first portion and a second end 144 opposite the first end 142. The second arm 145 extends outward from a second portion of the front surface 115, the second portion being spaced from the first portion, and includes a third end 146 engaging the second portion and a fourth end 148 opposite the third end 146. The curtain rod cradle 150 is configured to receive a curtain rod (not shown) that is secured within the curtain rod cradle 150 with a rod support set screw 152. The curtain rod cradle 150 is U-shaped, and has first and second vertical members 154, 156 and a base 155 extending between the first and second vertical members 154, 156. The first vertical member 154

has a hole 158 formed therein and is attached to the second end 144 of the first arm 140, and the fourth end 148 of the second arm 145 is attached to the cradle 150 such that the second end 144 and the fourth end 148 form an acute angle with each other. As will be described further, the bracket 100 is configured to mate with the fastening plate 120 and the fastening plate 120 is secured to a wall structure (not shown) by the finishing nails 126, 128, which insertably engage apertures 122, 124. The fastening plate 120 includes first and second sides, a first flange 125a extending outwardly from and along the first side, and a second flange 125b extending outwardly from and along the second side.

As shown in FIG. 2, a second embodiment of an exemplary fast fit bracket system 200 includes a bracket 210 and a fastening plate 220 having apertures 222, 224 to receive finishing nails 226, 228, respectively. In the embodiment shown, the bracket 210 includes a back portion 230, an arm 240, a first curtain rod cradle 250 and a second curtain rod cradle 252. The curtain rod cradles 250, 252 are configured to receive curtain rods (not shown) that are secured within respective curtain rod cradles 250, 252 with rod support set screws 254, 256. As will be described further, the bracket 200 is configured to mate with the fastening plate 220 and the fastening plate 220 is secured to a wall structure (not shown) by the finishing nails 226, 228.

As shown in FIG. 3, each of the brackets, for example, bracket 210, includes a back portion (i.e., the portion of the bracket 210 opposite the arm 240) configured with a channel 300. The channel 300 is formed by opposing side rails 310, 312 and a top rail 314. A lower portion 316 of the channel is open ended. The channel 300 is sized to snugly receive the fastening plate 220. More specifically, after the fastening plate 220 is secured to a wall structure, the channel 300 of the bracket 210 is slid over the fastening plate 220, securing the bracket 210 to the fastening plate 220 and thus to the wall structure. The top rail 314 of the channel 300 limits upward travel and acts like a stop when the bracket 210 is placed over the fastening plate 220.

The fastening plates 120, 220 shown above, generally require use of a hammer or screwdriver in conjunction with nails or screws to secure the fastening plates 120, 220 to any wall structure. However, manual insertion may be used when the wall structure is standard wall board. But there are times in which a tool-less system would be preferred. Referring now to FIG. 4, in an alternate embodiment, the fastening plates 120, 220 are replaced by a prong 400. The prong 400 includes an exposed portion 410 offset from two penetration portions 412, 414. A user presses the penetration portions 412, 414 into a wall structure and the exposed portion 410 remains visible. The exposed portion 410 is manually placed into the channel 300 until it abuts against the top rail 314, thus securing the bracket 110, 210 to the wall structure.

In FIG. 5, alignment of a prong 500 is shown relative to a channel 510 of a bracket 520. As described above, the channel 510 is slid over an exposed portion 530 of the prong 500 after penetration portions 540, 542 are placed with in a wall structure.

Referring now to FIG. 6, in one embodiment the fastening plates 120, 220 are replaced with a lengthened and shaped fastening plate 600 to increase to stability. The fastening plate 600 includes a tapered mid-section 610, an upper portion that includes apertures 620, 622 for use with nails or screws (not shown) that are used to secure the fastening plate 600 to a wall structure (not shown).

FIG. 7 illustrates an exemplary rear view of a fast fit bracket system 700 and FIG. 8 illustrates an exemplary bottom view of a fast fit bracket system 800.

FIG. 9 illustrates an exemplary side view of a fast fit bracket system 900.

The foregoing description of the preferred embodiments of the invention is by way of example only, and other variations of the above-described embodiments and methods are provided by the present invention. The embodiments described herein have been presented for purposes of illustration and are not intended to be exhaustive or limiting. Many variations and modifications are possible in light of the foregoing teaching. The invention is limited only by the following claims.

What is claimed is:

1. A method comprising the steps of:

(1) providing a curtain rod bracket assembly comprising a front bracket and a wall fastening plate;

the front bracket comprising:

a substantially rectangular back portion having a front 20 surface and a back portion channel with an upper stop member, first and second opposed side rails descending from the upper stop member, and a lower opening between the first and second side rails;

a first arm extending outward from a first portion of the 25 front surface, the first arm including a first end engaging the front surface and a second end opposite the first end;

a second arm extending outward from a second portion of the front surface, the second portion being spaced from the first portion, and the second arm being curved and including a third end engaging the second portion and a fourth end opposite the third end; the second arm extending outward from the front surface of the front bracket; and the first arm and the second arm being in 30 continuous contact with one another from the second and fourth ends through substantially a quarter of a length of each of the arms, the first and second arms forming an acute angle; the second arm is disposed below the first arm;

a curtain rod cradle with a U-shape, having a first and a second vertical member and a semicircular bottom base extending between the first and second vertical members; the second and fourth ends of the first and second arms engage the first vertical arm of the cradle, and at 35 least a portion of the semicircular bottom base extends below a lower surface of the first arm; wherein the first vertical member extends upwardly past a top surface of the first arm and has a hole formed therein; and

the wall fastening plate comprising:

two apertures formed side-by-side in an upper portion of the plate along a substantially horizontal line, each of the two apertures operative to accept a respective fastening means operative for fastening the wall fas-

tening plate to a wall; wherein each aperture is operative to accept a fastener axially received in the aperture; wherein the two apertures are the only openings in the plate;

5 a first side,

a first flange extending outwardly from and along the first side,

a second side, and

a second flange extending outwardly from and along the second side;

(2) positioning the wall fastening plate of the curtain rod bracket assembly against the wall;

(3) inserting a first securing object into a first of the two apertures of the wall fastening plate; wherein the first securing object is at an angle relative to the wall fastening plate and to the wall, and urging the first securing object through the first of the two apertures of the wall fastening plate and into the wall, whereby the first securing object enters the wall;

(4) inserting a second securing object into a second of the two apertures of the wall fastening plate; wherein the second securing object is at an angle relative to the wall fastening plate and to the wall, and urging the second securing object through the second of the two apertures of the wall fastening plate, whereby the second securing object enters the wall;

(5) sliding the back portion of the front bracket onto the wall fastening plate such that the back portion channel of the back portion receives the wall fastening plate therein, whereby the back portion of the front bracket is secured to the wall fastening plate and thus to the wall; and

(6) positioning a curtain rod within the curtain rod cradle; whereby the second arm supports the first arm at the curtain rod cradle with the acute angle.

2. The method of claim 1, wherein the first and second securing objects include nails.

3. The method of claim 2, wherein the urging step includes fixating the nails.

4. The method of claim 1, wherein the first and second securing objects include screws.

5. The method of claim 4, wherein the urging step includes rotating the screws.

6. The method of claim 1, wherein the first arm is substantially perpendicular to the first portion of the front surface.

7. The method of claim 1, wherein the first and second opposed side rails are disposed on opposite sides of the substantially rectangular back portion.

8. The method of claim 1, wherein the positioning in step (6) includes inserting an end of the curtain rod into the curtain rod cradle.
